UNITED STATES PATENT OFFICE.

FRED E. MILNER, OF MARKLE, INDIANA.

REMOVABLE ENGINE-CYLINDER LINING.

Application filed February 26, 1921. Serial No. 447,973.

To all whom it may concern:

Be it known that I, FRED E. MILNER, a citizen of the United States, residing at Markle, in the county of Huntington, State 5 of Indiana, have invented certain new and useful Improvements in Removable Engine-Cylinder Linings; and I do hereby declare the following to be a full, clear, and exact description of the invention, such as will enable others skilled in the art to which it 10 pertains to make and use the same.

This invention relates to new and useful improvements in engines and particularly to the cylinders thereof.

One object of the invention is to provide 15 an engine cylinder which can be taken apart for the purpose of repairs and adjustments.

Another object is to provide a lining for 20 the cylinder which may be removed and a new one placed therein when the old one wears out or becomes scored from the wearing action of the piston.

Another object is to provide a one piece cylinder lining which is formed with means 25 for effectively preventing any leakage through the joint of the cylinder block sections, or between the lining and the cylinder proper.

Other objects and advantages will be 30 apparent from the following description when taken in connection with the accompanying drawing.

In the drawing:

Figure 1 is a vertical longitudinal sectional view through a cylinder, of the gas engine type, equipped with the improved lining, the lining being shown in elevation.

Figure 2 is a vertical longitudinal sectional view through the cylinder and lining.

Figure 3 is a horizontal transverse sectional view through the cylinder and lining, on the line 3—3 of Figure 1.

Referring particularly to the accompanying drawing, 10 represents the lower portion of a gas engine cylinder and 11 the upper portion thereof, the said sections being secured together by means of the vertical bolts 12. The cylinder is formed with the bore 13, extending into both sections. At the lower

end of the portion of the bore in the upper section there is formed a surrounding bevel face 14, and at the upper end of the portion of the bore in the lower section is formed a similar bevel face 15. These two bevel faces,

when the cylinder sections are bolted together, form a V-shaped groove which extends around the wall of the bore of the cylinder. In the upper section, the wall of the bore is formed with a bevel shoulder 16, and in the lower end of the bore of the lower section there is formed a similar bevel shoulder 17. Snugly fitted into the bores of the sections of the cylinder is a sleeve 18 which forms the removable and renewable lining of the cylinder. The upper end of the lining 18 is beveled outwardly, as shown at 19 to fit snugly against the upper shoulder 16, while the lower end of the lining is outwardly beveled to fit snugly against the lower shoulder 17. These joints are preferably 70 ground joints so that the fit is perfect, when the cylinder sections are bolted together, thus preventing any leakage past either of the shoulders into the space between the lining and cylinder bore. Formed around the 75 outer face of the lining 18, adjacent the upper end, is a V-shaped rib 20 which snugly fits into the V-shaped groove formed by the cooperation of the bevel faces 14 and 15. The piston 21, with its rings 22, fit within 80 the bore of the lining sleeve 18.

Thus, when the lining becomes scored or oblate, from the side slapping action of the piston, it is not necessary to have the cylinder rebored, and over-sized pistons 85 placed therein. The upper section of the cylinder is removed, the lining slipped out, and a new lining of the size of the original one, before it had become worn, slipped 90 into the bore of the cylinder, and the piston replaced.

The lining is preferably formed from the same material as that of the remainder of the cylinder because of its molecular construction.

The cylinder sections are formed with the usual water jacket spaces 23 and 24, respectively.

Attention is called to the fact that it is not necessary to remove the pistons for the 100 purpose of removing the lining, or to remove and replace the piston rings.

What is claimed is:

The combination with an engine cylinder having a beveled shoulder at its upper end and an inwardly directed flange at its lower end, the inner face of which is beveled, of a removable lining therefor comprising a

cylindrical open-ended body having its lower end outwardly beveled with the said beveled portion resting upon the said flange, and having a V-shaped supporting rib circum-

scribing its outer wall adjacent the upper end of the cylinder.

In testimony whereof, I hereby affix my

true signature, in the presence of two witnesses.

FRED E. MILNER.
